ABSTRACT OF THE DISCLOSURE

A battery charging arrangement has a transformer-rectifier for producing direct current connected by two conductors to a battery for charging it; in one of the conductors is an SRC and a control circuit for the SRC which includes a valve responsive to the voltage of the battery to render the SRC conductive when the battery voltage drops so as to recharge the battery, and a Zener diode in parallel with the control valve of the circuit to regulate the voltage at which the second valve becomes operative; a light is so connected as to connect it to the battery if the alternating current fails.

This application is a continuation of application No. 584,002 filed Oct. 3, 1966 now abandoned and application No. 330,825 filed Dec. 16, 1963 now abandoned.

This invention relates to emergency electrical systems, and more particularly to emergency lighting and alarm systems.

An object of the invention is to provide a novel and improved emergency lighting and alarm system which may be readily installed in buildings and other structures as an adjunct to the normal lighting service to provide emergency facilities upon failure of said service.

Another object of the invention is to provide an improved emergency or stand-by apparatus as above set forth, which is extremely reliable and foolproof in its operation.

A further object of the invention is to provide an improved stand-by lighting and alarm apparatus in accordance with the above, which is relatively simple in construction, inexpensive to fabricate and economical to maintain.

A still further object of the invention is to provide an improved stand-by apparatus in accordance with the foregoing, which is trouble-free in operation and requires little or no servicing, or replacement of parts throughout an extended period of use.

Still another object of the invention is to provide an improved stand-by emergency lighting system which will set off an alarm in the event of failure of the power source thereof, and which will also provide an indication of fuse failure in the stand-by circuits.

A feature of the invention resides in the provision of a novel auxiliary power supply and control unit, which may be placed in a convenient location in the building, as determined by the available space.

A still further object of the present invention is to provide an improved auxiliary lighting or stand-by apparatus adapted to supply a multiplicity of stand-by circuits, wherein automatic energization of any one or several of said circuits is provided for automatically in response to failure of one or several of the regular service circuits.

A further feature of the invention is to provide an emergency lighting and alarm system which has no moving parts whatsoever, in as much as all operations are performed in conjunction with various solid state semiconductor devices. This is accomplished in both the bat-

tery charging and in the automatic connection of emergency electrical load.

A particular feature of the invention is the use of a Schmitt trigger circuit in conjunction with a Zener diode regulator to establish a fixed reference voltage at the emitter of the control transistor of the trigger circuit so that in battery charging, a precise switching voltage to a different charging rate can be achieved, and with a resulting lower voltage the hysteresis of the trigger circuit prevents the oscillating switching of the transistors of the trigger circuit.

Further objects and advantages of the invention will appear more fully from the following description, particularly when taken in conjunction with the accompanying drawings, which form a part thereof.

In the drawings:

FIG. 1 shows diagrammatically a circuit embodying the invention;

FIG. 2 shows part of a modified circuit; and

FIG. 3 shows a part of a further modification.

Referring to FIG. 1, the primary purpose of the invention as herein disclosed is to provide for the lighting of emergency lights 2 in the event of failure of the current in a conventional AC system 4 by means of a battery 6, and to provide for recharging of this battery automatically whenever its charge drops below a predetermined value.

The circuit as shown has a pilot light 8 connected to the main circuit, as well as the primary winding of a transformer 10. A midpoint of this secondary winding is connected to line 12, while the ends of the secondary winding are connected by rectifiers D₁ to line 14. Line 12 is connected to the positive terminal of the battery while line 14 is connected to the negative terminal through silicon-controlled rectifier 16, and, in parallel with it, resistance R₁₀ and rectifier D₂, these being joined at a common point b.

Resistances R₂ and R₃ are connected in series to line 12 and to the collector of transistor Q₁. The emitter of this transistor is connected through switch S₂ and resistance R₆ to point b. The base of transistor Q₁ is connected to a midpoint of resistance R₁ connected between lines 12 and 14. Zener diode Z is connected in a line running from a point between resistances R₂ and R₃ to line 14.

The resistance R₄ is connected at a point between resistance R₃ and the collector of transistor Q₁ to the base of transistor Q₂. The collector of transistor Q₂ is connected through a resistance R₇ to line 12, and its emitter is connected through resistance R₅ to resistance R₆.

The base of transistor Q₃ is connected between resistance R₇ and the collector of transistor Q₂. Its emitter is connected through resistance R₉ to the line 12, and its collector through the resistance R₅ to the SRC gate 16.

The base of transistor Q₄ is connected to a point between resistance R₉ and the emitter of transistor Q₃ and its emitter is connected to the line 12. Its collector is connected through pilot light P₂ to line 14.

The lamps 2 are connected at the side of the negative pole of battery b and at the other side of the collectors of transistors Q₁₂ and Q₁₃. The emitter of transistor Q₁₃ is connected to the positive side of battery 6 and its base is connected to the emitter of transistor Q₁₂. The base of transistor Q₁₂ is connected to the collector of transistor Q₁₁. The emitter of this transistor is connected to line 12 while its base is connected to line 12 through resistance R₁₃ and through resistance R₁₁ of rectifier D₂, D₂, connected across the secondary of transformer 10.

During normal operation, as will be explained herein-after, the battery 6 is kept at full charge. During this operation, the main line current at 4 is continuous, so that transformer 10 is energized. Through rectifier D₂,

D_2 , transistor Q_{11} is biased across resistance R_{11} and is conductive from line 12 to line 14. Q_{12} and Q_{13} are not conducting because Q_{12} is effectively shorted by Q_{11} and R_{12} . The lights are therefore not lighted. A condenser C is provided to filter the Q_{11} bias.

If the power fails, transformer 10 is no longer energized and Q_{11} is no longer conductive. Q_{12} and Q_{13} are then biased through their emitter-bases through R_{12} causing them to conduct and thus energize the emergency lights 2. To obtain an on-off bias to Q_{11} , a negative source is obtained directly from the alternating current source via independent rectification.

When normal power is restored, Q_{11} is again caused to conduct and the lights are cut off.

This lighting of the lights has caused a drain on battery 6. Assuming that the battery has been discharged to a substantial extent, then the following takes place when the power is restored and the emergency lights go off.

Current flows from voltage level a to b via: R_2 , R_3 , R_4 , Q_2 base-emitter, R_5 , and R_6 . With transistor Q_2 conducting, additional current paths are created. A second path forms through R_7 to Q_2 where it joins with the first path. This causes Q_3 to conduct and permits current to flow through: (a) Q_4 emitter-base to Q_3 emitter-collector, R_8 and SCR gate and (b) Q_4 emitter-collector and pilot light P_2 . The path through R_2 and Z establishes a definite voltage at junction b regardless of what the charging voltage is. This definite voltage is important as a reference for Q_1 .

By means of these paths, the SCR is constantly being fired and thus conducting, which shorts out R_{10} and allows a higher current to flow through the battery. Resistors R_4 , R_7 and R_8 are for biasing and thus control the voltages and consequent currents to Q_2 base, Q_3 base, and SCR gate to the desired values, respectively. Resistors R_2 , R_3 , R_5 and R_6 are primarily to limit current. Also R_2 and R_3 , being in series with R_4 , are part of the bias control of Q_2 .

When the battery charging having progressed to predetermined point where the battery should now be transferred, as indicated by the charging voltage, to a low charge current rate, the voltage across R_1 has reached a value such that voltage at junction a is at the desired value as to cause Q_1 to conduct. Upon Q_1 conducting, a path R_2 , R_3 , Q_1 collector-emitter, and R_6 is established. Since the resistance between junctions c and d via Q_1 is negligible, compared to path through R_4 , Q_2 , and R_5 , Q_2 is effectively shorted out and ceases to conduct.

With Q_2 non-conducting, Q_3 loses its bias and turns off. This in turn causes: (a) Q_4 to shut off, extinguishing pilot light P_2 , and (b) removes the SCR gate voltage and shuts off the SCR.

Current must now pass through R_{10} only, and thus is reduced to a much lower value or trickle rate which may be adjusted to desired value by varying the resistance R_{10} .

Immediately upon switching to lower trickle charge rate, there is an immediate drop to a lower charging voltage across the battery (and R_1).

Q_1 continues to conduct while the remainder of the transistors and the SCR remain off or non-conducting. This ability to resist changing back to the high charge condition (Q_2 on and Q_1 off) is due to the inherent nature or characteristic of the circuit used, in conjunction with associated resistors, and is referred to as circuit hysteresis. Although the voltage to Q_1 base has been slightly reduced and is below its original required firing voltages, it still continues to conduct. It will continue to conduct unless the voltage drops to a value below that required to turn on Q_2 . This drop below the turnoff voltage will occur only when the battery has discharged below the predetermined value because of charging failure and battery self discharge, or discharging of the battery into the load or emergency lights.

A power failure will cause the emergency lights to be energized and the charger shut off.

The immediate drain from the battery for the lights, removes the surface voltage from the battery and thus the voltage at junction a is less than the conducting voltage of Q_1 which causes it to shut off. Q_2 then resumes conducting. However, because there is no charging current present, there is no current flow through Q_3 and Q_4 . Accordingly the SCR and pilot light, P_2 , remain off.

The Zener diode, Z , has a fixed permanent voltage drop— V_z . Because of this, it frequently used as a voltage regulator. Thus when Q_2 is conducting there is a definite and fixed voltage at every point between + and — through Q_2 path. At point d , there is a voltage of —. This voltage is also the same at e . Thus the emitter of Q_1 , at point 3, is always at the definite voltage of —.

Now assume the pot R_1 has been adjusted so that it will have a null or zero point at a certain battery voltage equal to “—” + 0.3 v., or assume E = 3.0 volts, then the zero point would be 3.3 v. (The + 0.3 v. is the normal voltage increment required to turn on the transistor.)

Naturally as a battery is charged, it will start at less than this null voltage. As it becomes charged, the voltage at point f approaches the null point. Then at the null point Q_1 fires.

Without Zener Z to regulate and thus establish the fixed voltage of — at d and e , these points too would increase somewhat as battery voltage rises. Thus it would be nearly impossible to obtain 0.3 v. increment for the null point to occur. At least a definite switching voltage would not be possible without a definite fixed voltage E at the emitter of Q_1 .

Once Q_1 turns on, Q_2 is shut off due to to much less resistance being in the Q_1 circuit and greatly reducing the current available for the base-emitter or Q_2 —the great majority of current passes collector-emitter of Q_1 . While the battery charging voltage will be reduced below the original turning-on voltage, the fact that Q_1 stays on and Q_2 remains off is due to the hysteresis. Assuming that the battery was partially drained while the transistors were in this position (battery drain such as inadequate trickle charge), when the battery had dropped to a certain voltage at the end of the hysteresis limit, then Q_2 would come on and shut off Q_1 .

FIG. 2 shows a modification using a transistor rather than an SCR. Other than the portion shown, it is identical with FIG. 1.

The base of transistor Q_5 is connected to the collector of Q_3 , its emitter to line 12, and its collector to the bases of transistors Q_4 and Q_7 and through resistors R_9 to the collectors of these transistors. The resistance R_{10} is connected in parallel with transistors Q_6 and Q_7 .

If the battery has been discharged and is to be recharged at a high rate, current flows from voltage levels a to b via: R_2 , R_3 , Q_2 base-emitter, R_5 , and R_6 . With transistor Q_2 conducting, additional current paths are created. A second path is formed through R_7 to Q_2 where it joins with the first path. This causes Q_3 to conduct and permits current to flow through Q_4 to and through pilot light P_2 . Q_5 is not conducting because Q_3 has placed an effective short between Q_5 base and emitter. Thus the base current for Q_5 from battery-through R_8 is shunted through Q_3 collector-emitter.

The path through R_2 and Z establishes a definite voltage at junction b regardless of what the charging voltage is. This definite voltage is important as a reference for Q_1 .

Q_7 is biased via R_9 from its collector and thus permitting Q_6 to conduct. With Q_6 conducting, R_{10} is shorted out and allows a much higher charging current to flow through the battery. Resistors R_4 , R_7 and R_9 are primarily for biasing their respective transistors, while the remaining resistors are primarily to limit current flow.

When battery charging having progressed to a predetermined point where the battery should now be transferred to the low charge current rate, the voltage across R_1 has reached a value such voltage at junction a is at

a desired value so as to cause Q_1 to conduct. Upon Q_1 conducting, a path R_2 , R_3 , Q_1 collector-emitter, and R_7 is established. Since the resistance between junction c and d via Q_1 is negligible, compared to the path through R_4 , Q_2 , and R_5 , Q_2 is effectively shorted out and ceases to conduct.

With Q_2 non-conducting, Q_3 loses its bias and turns off. This in turn causes: (a) Q_4 to shut off, extinguishing pilot light P_2 , Q_5 is biased via R_8 and turns on to conduct current to and through R_6 . Under this situation the base voltage of Q_7 is reversed. With Q_7 losing its bias, it shuts off and would shut off Q_6 , except for bias via R_{10} . Current is now reduced to a much lower value for trickle rate which may be adjusted to any desired value by varying the resistance of R_{10} . The larger the resistance, the lower the charging rate upon switching to a lower charging rate, Q_1 and Q_5 continue to continue to conduct while the remainder of transistors remain off or non-conducting.

If a power failure causes the load to be energized and the charger shut off, the lower battery voltage after use causes Q_1 to revert to its non-conducting state while Q_2 returns to conducting state when normal power is restored and charging resumes.

Inasmuch as the SCR and transistors act purely as "solid-state relays" or remote switches, a relay of suitable design could be used in place of these items. In models built using a relay, a current sensitive relay was used—0.35 watts, 400 ohms. Such a relay usually has low power contacts and thus in some instances it would be used to trigger another relay which would have heavier contacts required for higher currents. As shown in the drawing, FIG. 3, the pilot light is connected at the junction of the diode and contacts G_1 instead of an additional transistor stage previously used, as Q_4 in the SCR circuit.

The switching "On" and "Off" of the transistors is the same as in the previous figures, the only difference being that Q_3 feeds the sensitive relay coil G instead of the SCR gate with its voltage dropping resistor. Obviously the pilot light is on only when the relay contacts are closed since there can be no reverse current flow through the diode.

To manually place the battery on high charge rate regardless of battery voltage, opening of S_2 , in the emitter circuit of Q_1 , prevents the Q_1 circuit from effectively shorting out Q_2 circuit, and thus Q_2 remains conducting for high charge regardless of battery voltage.

Temperature compensation of the battery voltage at which the circuit should switch from high to low charge may be achieved by inserting a thermistor in the sensing circuit. By selecting the correct thermistor, compensation for an increase in temperature by switching at a lower battery voltage is achieved.

The use of a breaker as a current limiting device which will automatically reset itself when the current overload has been removed is preferably to normal fusing and manual reset breakers.

In circuits exceeding the approximately 70 volts necessary to ignite a neon light bulb, such a light bulb with suitable current limiting resistor may be used to shunt a current limiting device to indicate and signal an alarm

when the current limiting device is open and non-conducting.

While we have described herein some embodiments of our invention, we wish it to be understood that we do not intend to limit ourselves thereby except within the scope of the claims hereto or hereinafter appended.

What is claimed is:

1. In a battery charging arrangement having two conductors for connection to the terminals of a battery and a direct current source, first valve means in one of said conductors, a control circuit for said first valve means connected between said conductors and including means responsive to the reduction of the voltage of the battery below a predetermined amount to render said first valve means conductive, said control circuit further including a second valve means operative when conducting to render said voltage-responsive means inoperative, whereby said first valve means is rendered non-conductive, said circuit having a substantial impedance, and voltage-dependent valve means connected across said conductors in parallel with said second valve means to regulate the voltage at which said second valve means becomes operative.
2. In combination with an arrangement as claimed in claim 1, a source of direct current and a battery connected to said conductors, a load, and means, responsive to the failure of the direct current source, to connect said load to said battery.
3. In an arrangement as claimed in claim 1, a relatively high resistance connected in parallel with said first valve means.
4. In a battery charging arrangement having two conductors for connection to the terminals of a battery and a direct current source, first valve means in one of said conductors, a Schmitt trigger circuit connected between said conductors and including means responsive to the reduction of the voltage of the battery below a predetermined amount to render said first valve means conductive, said circuit including a second valve means operative when conducting to render said voltage-responsive means inoperative, whereby said first valve means is rendered non-conductive, and a voltage-dependent Zener diode connected across said conductors in parallel with said second valve means to regulate the voltage at which said second valve means becomes operative.
5. In an arrangement as claimed in claim 4, a relatively high resistance connected in parallel with said first valve means.
